[57] CLAIM

The ornamental design for a housing for fan accessory for heater, substantially as shown and described.

DESCRIPTION

FIG. 1 is a top left perspective view of a housing for fan accessory for heater, showing my new design;

FIG. 2 is a right perspective view thereof;

FIG. 3 is a left side elevational view thereof;

FIG. 4 is a front elevational view thereof.

The broken line disclosure of a heater in FIGS. 1 and 2 is for illustrative purposes only and forms no part of the claimed design.

The rear and bottom sides of the blower are substantially plain and unornamented.
